(57) **CLAIM**

The ornamental design for the mobile device with graphical user interface, as shown and described.

DESCRIPTION

A portion of the disclosure of this patent document contains material to which a claim for copyright is made. The copyright owner has no objection to the reproduction of the patent document or the patent disclosure, as it appears in the U.S. Patent Office records, but reserves all other copyrights whatsoever.

The FIGURE is a front view of the mobile device with graphical user interface.

The portions of the display screen shown in broken line form no part of the claimed design.
